UNITED STATES PATENT OFFICE.

WILLIAM J. DILLON, OF GRAND RAPIDS, MICHIGAN.

TAUTENING MECHANISM FOR UPHOLSTERY BANDS.

Application filed November 12, 1926. Serial No. 148,091.

The present invention relates to tautening means, particularly such as may be employed for tautening furniture upholstery bands; and its object is to provide improved mechanism for tautening such bands while being secured to articles of furniture and the like.

This and any further or more specific objects hereinafter appearing are attained by, and the invention finds preferable embodiment in, the mechanism hereinafter particularly described in the body of this specification and illustrated by the accompanying drawings, in which:

Figure 1 is a front view of mechanism for tautening the upholstery-supporting bands of such articles of furniture as "davenport" lounges and the like, while such bands are being secured to the furniture frame;

Figure 2 is a sectional view of said mechanism and of a davenport-lounge frame and a stool supporting the same, taken on vertical planes corresponding to line 2-2 of Figure 1; and

Figure 3 is a top plan view of guides for the sliding movement of the tautened bands, and of adjacent parts of the mechanism.

Considerable difficulty is found in tautening and holding taut the flexible bands or strips of webbing or the like employed to support the upholstery, cushions, etc. of such articles of furniture as davenport-lounges or other seats, and in thus tautening a plurality of such bands uniformly in relation to each other. It is the object of the present invention to obviate such difficulty.

In the embodiment of the invention illustrated by the drawings, tautening mechanism is shown comprising a frame, comprising several detachably connected units, each of which may embrace a plurality (three in the construction illustrated) of band-tautening means. In said embodiment, the frame comprises upright members 1 joined by horizontal rods 2, 3, 4 extending through openings 5 in the uprights and detachably held therein by set screws 6. Each of the several units (two of which are shown in Figure 1) thus connected comprise a pair of the laterally spaced uprights 1, one of which as shown in Figure 1 may be common to two such adjoining connected units.

Each such unit comprises one or more (three in the construction illustrated) tautening means, and has a shaft 8 rockably mounted in bearings 9 on the frame's uprights, one such shaft answering for all the tautening means of each unit. This shaft

has means for detachably engaging the work, i. e., the several bands 7 of webbing or the like employed to support furniture upholstery, and to tighten such bands during the process of securing the same on the frame of a lounge 10 or other article of furniture. Such engaging means, as illustrated, are the pointed spurs 12 extending radially from said shaft and adapted to pierce the bands 7 passing over the shaft. In this tautening operation, the free ends 13 of the bands are nailed or otherwise secured to the rear horizontal rail 14 of the lounge, and the bands are then engaged by the spurs 12, whereupon the shaft 8 is rocked counter-clockwise (see Figure 2) thus tautening all the bands simultaneously and uniformly. The bands are now secured to the front horizontal rail 16 of the lounge as by nails 17. The secured lengths of the bands are now severed from the rest of the band strips and the outer ends of the secured lengths may be doubled back and nailed down in the same manner as are their inner ends 13 secured to the rear rail 14. In this operation of tautening and securing the bands to the frame of the lounge, the lounge may be supported on a suitable bench 18, the uprights 1 resting on the floor 19, and abutting at their rear sides on the frame of the lounge. The free ends of the bands being secured at 13 on the rear rail 14, equal weights 37 may be hung on the bands to tension the same uniformly before being engaged by the spurs 12. The shaft 8 is now rocked to tighten the bands to the degree required in the finished product by suitable means. Such means may manifestly be of various forms or types; in the illustrated construction these means comprise a crank arm 20 carried by the shaft, a pedal lever 21 fulcrumed at 22 on one of the uprights and a link 23 connecting this lever with said crank, a spring 24 serving to rock the shaft back to initial position for a subsequent operation. Rolls 25 of the band strips are shown carried by supports, the semi-circular boxes 26, held on the rods 3, 4, and having sides 27 holding the rolls in operative alignment with the band-engaging spurs 12 carried by the shaft 8. It will be seen that the free ends 13 of the rolls of band strips are passed upwardly and over the shaft 8 and are then drawn far enough to be secured to the lounge's rear rail 14, pedal lever 21 being released so that the spurs 12 are turned inwardly too far to engage the bands. The pedal lever being now pressed down, the

shaft 8 is now rocked to tighten the bands to the degree required in the finished product by suitable means. Such means may manifestly be of various forms or types; in the illustrated construction these means comprise a crank arm 20 carried by the shaft, a pedal lever 21 fulcrumed at 22 on one of the uprights and a link 23 connecting this lever with said crank, a spring 24 serving to rock the shaft back to initial position for a subsequent operation. Rolls 25 of the band strips are shown carried by supports, the semi-circular boxes 26, held on the rods 3, 4, and having sides 27 holding the rolls in operative alignment with the band-engaging spurs 12 carried by the shaft 8. It will be seen that the free ends 13 of the rolls of band strips are passed upwardly and over the shaft 8 and are then drawn far enough to be secured to the lounge's rear rail 14, pedal lever 21 being released so that the spurs 12 are turned inwardly too far to engage the bands. The pedal lever being now pressed down, the

shaft 8 is now rocked to tighten the bands to the degree required in the finished product by suitable means. Such means may manifestly be of various forms or types; in the illustrated construction these means comprise a crank arm 20 carried by the shaft, a pedal lever 21 fulcrumed at 22 on one of the uprights and a link 23 connecting this lever with said crank, a spring 24 serving to rock the shaft back to initial position for a subsequent operation. Rolls 25 of the band strips are shown carried by supports, the semi-circular boxes 26, held on the rods 3, 4, and having sides 27 holding the rolls in operative alignment with the band-engaging spurs 12 carried by the shaft 8. It will be seen that the free ends 13 of the rolls of band strips are passed upwardly and over the shaft 8 and are then drawn far enough to be secured to the lounge's rear rail 14, pedal lever 21 being released so that the spurs 12 are turned inwardly too far to engage the bands. The pedal lever being now pressed down, the

shaft 8 is now rocked to tighten the bands to the degree required in the finished product by suitable means. Such means may manifestly be of various forms or types; in the illustrated construction these means comprise a crank arm 20 carried by the shaft, a pedal lever 21 fulcrumed at 22 on one of the uprights and a link 23 connecting this lever with said crank, a spring 24 serving to rock the shaft back to initial position for a subsequent operation. Rolls 25 of the band strips are shown carried by supports, the semi-circular boxes 26, held on the rods 3, 4, and having sides 27 holding the rolls in operative alignment with the band-engaging spurs 12 carried by the shaft 8. It will be seen that the free ends 13 of the rolls of band strips are passed upwardly and over the shaft 8 and are then drawn far enough to be secured to the lounge's rear rail 14, pedal lever 21 being released so that the spurs 12 are turned inwardly too far to engage the bands. The pedal lever being now pressed down, the

shaft 8 rocks turning the spurs outwardly and into holding engagement with the bands; and, this rocking movement continuing, the bands are tautened as above explained. To cause the spurs to surely engage in the bands, these bands pass through guides 28 on the frame of the mechanism and open at their sides 31, the front portions 29 of these guides holding the bands down on the shaft 8 so that the spurs may engage the bands. These guides have openings 30 through their front portions 29, so that the spurs may pass therethrough in the rocking movements of the shaft.

In order to adapt the mechanism to furniture articles of different shapes or front contour, abutments adapted to rest on the front of such articles are provided in the form of eccentric members 32 mounted turnably at 33 on the uprights 1, and adapted to be turned to positions in which they may be fixed by set screws 34; and to prevent marring such articles the abutting edges of these eccentrics are furnished with pads 35 of soft material. The shaft's flanges 38 serve to guide the bands and hold the same against edgewise movement. It is manifest that this mechanism or some detached unit or single member thereof may be employed for tautening bands lengthwise of the lounge, or the bands of some smaller article of furniture as a chair or other seat.

The invention being intended to be pointed out in the claims, is not to be limited to or by details of construction of the particular embodiment thereof illustrated by the drawings or hereinbefore described:

What is claimed is:

1. In tautening mechanism of the character described: a frame; a shaft rockably mounted thereon and having means for detachably engaging the work; means whereby the shaft may be rocked and releasably held in rocked position; an eccentric abutment mounted on the frame turnably to fixed positions. 40

2. In a structure of the character described: a frame comprising end uprights and an intermediate upright, detachably connected spacedly side by side; shafts rockably mounted on the end uprights respectively and rockably mounted detachably on the intermediate upright, each shaft having means for detachably engaging the work; means whereby the shafts may be rocked and releasably held in rocked position. 50

3. In tautening mechanism of the character described: a frame; a shaft rockably mounted thereon and having spurs adapted to piercingly engage the work; means whereby the shaft may be rocked and releasably held in rocked position; a guide on the frame for the work adapted to slidably hold the work in spur-engaging position and having openings through which the points of the spurs projecting through the work are adapted to pass in the rocking movement of the shaft. 60

In testimony whereof I have hereunto set my hand at Grand Rapids, Michigan, this 3rd day of November, 1926.

WILLIAM J. DILLON.
